UNITED STATES PATENT OFFICE.

LEONARD P. LIDBACK, OF HONOLULU, TERRITORY OF HAWAII.

AIRSHIP.

Application filed February 1, 1928. Serial No. 251,129.

My invention relates to improvements in airships, and it consists in the combinations, constructions, and arrangements hereinafter described and claimed.

5 An object of my invention is to provide an airship that combines the lighter-than-air craft principle with the heavier-than-air craft principle. The device employs a gas containing bag having a great lifting power, 10 and a plurality of air plane wings that aid in lifting the airship, and in keeping it on an even keel when the ship is flying through the air.

15 A further object of my invention is to provide a device of the type described, in which the bulk-heads separating the gas bag into compartments are dished-type. The wings are disposed in sets and I have shown three wings in each set, and have further shown 20 three sets on each side of the gas bag. The passenger cabin is swung beneath the gas bag.

25 Other objects and advantages will appear in the following specification, and the novel features of my invention will be particularly pointed out in what I hereinafter claim.

My invention is illustrated in the accompanying drawing forming a part of this application, in which:

Figure 1 is a front elevation of the device; 30 and

Figure 2 is a side elevation of the device.

In carrying out my invention I provide a gas bag 1 of conventional shape. This bag is preferably covered with beryllium 35 skin, and is made gas tight. I do not employ a plurality of gas bags within the cigar-shaped container, as is the usual practice, but instead I provide a covering which in itself is gas tight. The present airship, as 40 shown in the drawing, is designed for carrying a great load. The diameter of the gas container 1 is one hundred and thirty feet at is maximum. The length of the container 1 is approximately eight hundred feet. A 45 container of such size will hold substantially 10,000,000 cubic feet of hydrogen gas.

In Figure 2 I have shown the container 1 as being provided with a plurality of dished-type bulk-heads 2. I have found that bulk-heads of this shape are stronger than flat ones. These bulk-heads divide the container

1 into a plurality of gas receiving compartments 3, and also add rigidity to the container.

In Figure 2 I show three sets of wings indicated generally at 4, and Figure 1 shows that these wings are disposed on both sides of the container 1. Each set of wings consists of three wings 5 that project laterally from the container 1. The distance from the tip 55 of one wing to the tip of the wing on the opposite side is approximately two hundred and fifty feet. There is a space of twenty feet between each wing and a wing disposed above or below. It will also be noted from 60 Figure 1 that the lowermost wing is continuous from end to end, and cuts across the entire airship. This lower wing 5' has pontoons 6 disposed at its extremities. These pontoons rest upon the water and help stabilize the airship when floating. Each pontoon 65 is large enough to carry a sponson tank 7 that can hold approximately six thousand gallons of gasoline.

Gasoline may be pumped from the tanks 7 70 to gravity tanks 8 by a mechanism not shown. These gravity tanks 8 are disposed in the upper wings 5 and are designed to carry six hundred and seven hundred and fifty gallons of gasoline. The upper tank 8' carries six 75 hundred, while the lower tank 8 carries seven hundred and fifty. These tanks feed motors 9 and 9', which develop a horsepower of twelve hundred and fifty and seven hundred and fifty, respectively. It should be noted 80 that the width of the wings is fifty feet, thus providing ample space for carrying the tanks 8 and 8'.

The airship is guided in its movement by the elevators 10 and rudders 11. I have shown 85 six engines 9 and 9' on each side of the container 1. These engines actuate propellers 12, which in turn give the necessary force to carry the airship through the air.

A passenger cabin 13 is swung beneath the 90 container 1 and extends substantially throughout the greater part of the length of the container. This cabin is large enough to carry freight and merchandise, other than passengers. Compartments for stowing heavy 95 freight or merchandise will be located directly under each set of wings.

The following gives the approximate lifting power of the airship when constructed of the size already mentioned:

5	Weight of air displaced at sea level	807,280 lbs.
5	Weight of 10,000,000 cu. ft. hydrogen gas	55,900 lbs.
	Total lifting power of gas at sea level	751,380 lbs.
	Weight of $\frac{1}{8}$ " thick shell (beryllium) and (stiffening girders)	320,000 lbs.
	Weight of $\frac{1}{8}$ " thick bulk-heads (beryllium) and (stiffeners)	87,500 lbs.
10	Weight of planes as shown on sketch	75,000 lbs.
10	Weight of 6 1250 h. p. engines and 6 750 h. p. engines	25,000 lbs.
	Total lifting power of hydrogen gas	507,500 lbs.
	Total weight of ship and engines gas	751,380 lbs.
15	Remaining buoyancy for fuel and tanks	243,880
15	Total plane surface	50,000 sq. ft.
15	Total lift of plane at 10 lbs. per sq. ft.	500,000 lbs.

From the above it will be noted that the buoyancy of the hydrogen gas compensates for the weight of the airship complete with engines, fuel, and equipment, leaving the entire lift of the wings 5 and 5', for supporting

a useful load of approximately two hundred and fifty tons of passengers, mail, and other cargo. The fuel is carried in the tanks 7 and these tanks are disposed at the extremities of the wings, in order to reduce fire-hazard.

Although I have shown and described one embodiment of my invention, it is to be understood that the same is susceptible of various changes and I reserve the right to employ such changes as may come within the scope of the invention as claimed.

I claim:

An airship having a container for gas, a boat-shaped cabin swung from the bottom of the container, a plurality of sets of wings projecting laterally on both sides of said container, the lowermost wings of each set extending entirely across the ship and on top of the cabin, and gasoline containing pontoons disposed at the extremities of the lower wings.

LEONARD P. LIDBACK.
